CUT-OFF MECHANISM

Karl E. Garling, Newark, N. J.

Application December 1, 1931. Serial No. 578,296

5 Claims. (Cl. 164—60)

Among the principal objects which the present invention has in view are: To provide a cutter adapted to operate upon a moving object while travelling therewith at the speed of travelling 5 of said object without bashing or injuring the sides of the severance; to provide a cutting blade and means for moving the same into a travelling object and perpendicular to the path of travel thereof, and to move in synchronism therewith in the direction of travel of said object; to provide a circular cutting disk and means for advancing the same transverse to the line of travel of an object to be severed and in synchronized speed with the article being severed.

Drawings

Figure 1 is a plan view of the cutting mechanism referred to.

20 Figure 2 is a sectional elevation thereof, the section being taken on the line 2—2 in Figure 1.

Figure 3 is a detailed view showing an elevation of a part of the driving mechanism for moving the cutter blade into, out of, and lengthwise, with the object to be cut.

25 Figure 4 is an elevation of a portion of a mechanism employed for guiding the article to be cut.

Description

30 The mechanism herein disclosed is employed principally in connection with the manufacture of sipper straws or paper tubes made in imitation of straws used principally for dispensing 35 soda water and similar liquids.

These straws are primarily formed as elongated tubes of small diameter, at the time of forming being moved at a very rapid rate. This tube is run through guide tubes 9. The tube 9 40 is formed in two sections as shown in Figure 4 of the drawings, the sections being separated to provide a gap 10 therebetween. It is through this gap that the cutting blade or disk 11 is extended by the crank arm 12, as the same is 45 gyrated by the shaft 13, at the lower end of which is the miter gear 14. Power is imparted to the gear 14 through the matched gear 15 and shaft 16.

The crank arm 12 and the crank arm 17 are 50 of the same length and are arranged so that the movements of the two crank arms are synchronized. To this end the shaft 16 is provided with a spiral gear 18 which is meshed with a second and similar gear 19 meshed to the shaft 20 on 55 which the crank arm 17 is fixedly mounted.

It will be understood that the gears 14 and 15 are matched as are gears 18 and 19, the length of the arms 12 and 17 being similar, and the shafts on which they are mounted having the same rate of rotation, the swing or rotation of 60 said arms are identical and therefore the parts carried therewith moved in synchronism.

The guide tubes 9 are held rigidly on a block 21. The block 21 as seen best in Figure 2 of the drawings is slidably mounted on the stub shafts 65 22, suitable bushings being provided therefor. On the under side of the block 21 is cut a slot indicated by dotted lines in Figures 1 and 2. Mounted in the slot 23 is a running block 24, which block is pivotally mounted on a spindle or 70 short shaft 25 indicated by dotted lines in Figure 2 of the drawings.

The result of this construction is as follows: 75 When the shaft 20 is rotated, the arm 17 is gyrated about the center of said shaft with the result that the block 24 slides lengthwise of the slot 23 moving the block 21 on the stub shaft 22 back and forth on said shafts. This provides for a movement of the guide tubes 9 in parallel 80 relation to the said stub shafts and in the line of the delivery of the tubes formed, the sip straws moving therethrough.

The shaft 13 moves in timed relation with the shaft 20 with the result that the arm 12 is gyrated in timed relation to the arm 17, with the result that the cutting blade 11 is advanced into and withdrawn from the path of the straw tube and into and from the gap 10 between the tubes 9. Also during the time when the tubes 9, containing 90 the straw tube, are in longitudinal motion, the blade 11 has a motion axially parallel thereto and travels in synchronized movement therewith. The blade 11, however, is maintained in its dependent relation to said path of movement by the gear train indicated by the numerals 95 26, 27, 28, 29 and 30.

The gear 26 is made fast on the shaft 31, shown best by dotted lines in Figure 2 of the drawings. The shaft 31 is pinned to the journal block 32. The journal block 32 forms a journal 100 to mount the short shaft 33 on which the blade 11 is secured. On the shaft 33 also there is mounted the pulley 34 driven by a belt 35 from an independent source of power.

The twin gear 27 is loosely mounted on the shaft 13 and is meshed with the gear 28 that is driven through the gears 29 and 30 and the shaft 36 which is operatively connected with the shaft 16 through the miter gears 37.

The gear train 27, 28, 29 and 30 are so constructed as to impart one complete revolution to the gear 26 during the complete gyration of the arm 12. This ratio thus established results in maintaining the blade 11 in transverse or perpendicular relation to the straw tube and the tubes 9 during the complete gyration of the arm 12, while the arm 12 being synchronized in its gyration with the arm 17, secures for the blade, a movement lengthwise of the travel of the straw tube, accurately synchronized with the said travel of the straw tube.

From the foregoing it will be seen that the movement being a continuous operation without thrust or jar of elements, the mechanism is smoother running with less noise and wear on the mechanism to which it may be attached.

I claim:

1. In combination with a paper tube forming mechanism for forming and continuously advancing a tube, a cut-off mechanism for said tube comprising, a cutter blade disposed in perpendicular and juxtaposed relation to said tube, a pivotal mounting for said blade, means for rotating said blade, a gyratory support for said pivotal mounting, means for maintaining said blade in constant perpendicular relation to said tube, said means embodying a mechanism for rotating said pivotal mounting in a direction contrary to the rotation of said gyratory support.

2. In combination with a paper tube forming mechanism for forming and continuously advancing a tube, a cut-off mechanism for said tube comprising, a cutter blade disposed in perpendicular and juxtaposed relation to said tube, a pivotal mounting for said blade, means for rotating said blade, a gyratory support for said pivotal mounting, means for maintaining said blade in constant perpendicular relation to said tube, said means embodying a driving mechanism for rotating said gyratory member, and means operatively connecting said driving means and said pivotal mounting for said blade for rotating said mounting in a direction contrary to the rotation of said gyratory support.

3. In combination with a paper tube forming mechanism for forming and continuously advancing a tube, a cut-off mechanism for said

tube comprising, a cutter blade disposed in perpendicular and juxtaposed relation to said tube, a pivotal mounting for said blade, means for rotating said blade, a gyratory support for said pivotal mounting, means for maintaining said blade in constant perpendicular relation to said tube, said means embodying a driving mechanism for rotating said gyratory member, and means operatively connecting said driving means and said pivotal mounting for said blade for rotating said mounting in a direction contrary to the rotation of said gyratory support, said means comprising a train of gears operatively connected and arranged to rotate said pivotal mounting as above specified.

4. In combination with a paper tube forming mechanism for forming and continuously advancing a tube, a cut off mechanism for said tube comprising, a crank arm, a journal block rotatably carried at an outer part of the crank arm and having a journal transverse thereof, a cutter rotatably mounted by said journal, a train of gears for rotating said journal block, and driving connections for rotating the said crank, said driving connections and train of gears being interconnected for synchronizing rotation of the crank arm and rotation of the journal block for maintaining the cutter normal to the tube being cut during the cutting operation.

5. In combination with a paper tube forming mechanism for forming and continuously advancing a tube, a cut off mechanism for said tube comprising a crank arm, a journal block rotatably carried at an outer part of the crank arm and having a journal transverse thereof, a cutter rotatably mounted by said journal, a train of gears for rotating said journal block, driving connections for rotating the said crank, said driving connections and train of gears being interconnected for synchronizing rotation of the crank arm and rotation of the journal block for maintaining the cutter normal to the tube being cut during the cutting operation; a straw guide normal to the cutter, and means for reciprocating said straw guide simultaneously and in synchronism with movement of the cutter in an axial direction.
